(57) **CLAIM**

I claim the ornamental design for a vehicle roof rack clamper, as shown and described.

DESCRIPTION

FIG. 1 is a Perspective view of a vehicle roof rack clamper showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof; and,

FIG. 7 is a Bottom view thereof.

1 Claim, 7 Drawing Sheets

FIG. 3

FIG. 4

FIG. 5

FIG. 6

FIG. 7
